CANOPY TOP FOR BICYCLE

Herbert Odell Stith, Jr., 3309 Sepulveda Blvd.,
Manhattan Beach, Calif. 90266

Filed Jan. 31, 1969, Ser. No. 15,580

Term of patent 7 years

Int. Cl. D12—14

U.S. Cl. D90—1

FIGURE 1 is a perspective view of a canopy top for a bicycle showing my new design;

FIGURE 2 is a front elevational view thereof;

FIGURE 3 is a side elevational view thereof; and

FIGURE 4 is a top plan view of the same.

I claim:

The ornamental design for a canopy top for bicycle, substantially as shown.
